J. W. Hatchet of Bedford Co. Virginia 9347X
Letters Patent.

The schedule referred to in these Letters Patent and making part of the same, containing a description in the words of the said J. W. Watcher himself of his improvement in the machine for peeling apples and peaches. -

To all to whom these presents shall come: Be it known that J. J. W. Hatcher of the County of Bedford and State of Virginia have invented a new and useful improvement in a machine for peeling peaches, Apples, and that the following is a full and exact description thereof.

1st. At Blinch. 2nd a cogwheel & axle or mitalas with a handle or crank to turn with the wheel about 11 or 12. inches in diameter with about 30 cogs, set up on 2 upright posts 3rd a small cogwheel say 3 inches diameter with 10 cogs placed to the rear of the large cog wheel to be turned by it the axle of the small cog wheel in form of a screw 4th a fork or forked spindle with a wheel fixed on two upright posts, a band around the large cog wheel and around the wheel to turn the folk on which the apple or peach is to be stuck. 5. a small wheel with 10 notches is fixed under and turned by the axle or screw of the small cog wheel the axle of this small wheel extends within about 2^{1/2} inches of the end of the folk so as to come with the centre of the peach or apple when stuck on the folk near the wheel is a piece let in to the axle with a mortis to receive end of the piece on which the knife is fixed also near the other end of the axle is another piece let in as before a part taken out so as to form a folk or two uprights or posts in the axle. 6. a piece extending from the post or upright near the small wheel with 10 notches to the folk tenanted and pinned in this post so as to play to and from the axle, and between posts near the other end of the axle which confines it in such manner as to give it a circular motion with the axle also permitting the end over the folk to play to and from the end of the apple or peach as it may be large or small, the end of this piece is to be about 1^{1/2} inches wide & $4\frac{1}{2}$ thick across this end is to be fixed a knife leaving space enough between the knife and piece to permit the peeling

to pass between, & a spring to be applied either on top or underneath the piece on which the knife is fixed to bear it to the apple or peach. This is done by fastening one end to the axle and the other to the piece on which the knife is fixed, by turning the big cog wheel it gives motion to the whole, as may be seen by the drawing below. That portion or part I claim as my own, is the part giving motion to the knife -
